UNITED STATES PATENT OFFICE.

JAMES BAGLEY, OF BEDFORD, MASSACHUSETTS, ASSIGNOR, BY MESNE ASSIGNMENTS,
TO ALICE L. PFEIFFER, OF BEDFORD, MASSACHUSETTS.

PILE WIRE.

Application filed December 11, 1925, Serial No. 74,742. Renewed July 21, 1926.

The invention relates to pile cutting units employed in looms which weave pile fabrics, to cut the loops of the fabric, each unit including a body portion, a blade holder, and 5 a blade detachably secured to the holder, the unit being operated by well known means, to cause the blade to cut a row of loops in the usual manner.

The object of the invention is to provide 10 an improved construction of the holder, whereby it is adapted to firmly secure the blade and permit the quick and convenient removal and replacement of the latter.

Of the accompanying drawings forming a 15 part of this specification,—

Figure 1 is a side view, showing the holder without the blade.

Figure 2 is a side view of the blade.

Figure 3 is a side view, and Figure 4 an 20 edge view, showing the body portion of the wire, the holder, and the blade assembled.

Figure 5 is a section on line 5—5 of Figure 1.

Figure 6 is a section on line 6—6 of 25 Figure 3.

Figure 7 is a section on line 7—7 of Figure 3.

Figure 8 is a section on line 8—8 of Figure 3.

30 Figure 9 is a view similar to Figure 3, showing an additional abutment.

The drawings show the pile wire considerably enlarged.

The same reference characters indicate the 35 same parts in all of the figures.

12 designates the body portion of a pile wire, which may be of any suitable construction, and operated by any suitable means. Fixed to and projecting outward from one 40 end of the body portion, is a blade-holder, adapted to detachably confine a blade 13. Said holder is made from sheet metal and comprises a gripping-jaw 14, preferably including a head 15, a jaw 16, opposed to the 45 jaw 14, and a neck 17 connecting the jaws. The jaws 14 and 15 are adapted to bear yieldingly on opposite sides of the blade, and the neck 17 constitutes a blade-back abutment, for the back of the blade 13, the 50 back being the unsharpened longitudinal edge opposite the sharpened edge 13 a.

The holder is provided at the inner ends 55 of the jaws with an inner abutment 18, for the inner end of the blade. Said abutment may be provided by a member inserted be-

tween, and soldered or brazed to, the inner sides of the jaws, or it may be the outer end of the body portion 12.

The head portion 15 of the jaw 14 bears on the major portion of one side of the blade, 60 and is provided with an outer abutment 19, for the outer end of the blade, and with a holding-down abutment 20, bearing on a portion of the cutting edge of the blade. The abutments 17, 18, 19 and 20 collectively 65 confine the blade against endwise and edge-wise movements, when the blade is interposed between the jaws and laterally confined thereby. The abutments 19 and 20 are preferably formed by inwardly displacing 70 portions of the metal of the head portion 15, as best shown by Figures 6 and 7.

Owing to the fact that the jaws bear 75 yieldingly on the sides of the blade, the outer end portion of the blade may be sprung or displaced laterally, as indicated by dotted lines in Figures 6 and 7, to disengage the blade from the abutments 19 and 20, and thus permit the removal of the blade from the holder, the jaw 16 yielding, to permit 80 this displacement.

The inner abutment 18 is formed to hold 85 down the inner end of the blade, and prevent outward displacement thereof from the holder. In this instance, the abutment has an inclined edge bearing on the inclined inner end of the blade, as indicated by dotted lines in Figure 3. In removing the blade, its outer end portion is first disengaged from the abutments 19 and 20, and 90 then the blade is withdrawn from the jaws.

To facilitate the displacement of the outer end portion of the blade, I provide the head portion 15 with an opening 22, in which a prying tool 23, shown by dotted lines in 95 Figures 3 and 4, may be inserted and manipulated to force said end portion away from the extension.

When the pile wire is of maximum width, the blade-back abutment may include an 100 abutment member 25, formed like the abutments 19 and 20, on the head portion of the jaw 15, and arranged to bear on the outer end portion of the blade-back, as shown by Figure 9, the inner end portion of the blade-back bearing on the neck 17. In this embodiment, the blade-back abutment includes 105 two members, one of which is the member 25, and the other the neck 17.

The jaw 16 may be relatively short, as 110

shown by Figure 9, so that its outer end is spaced rearward from the abutments 19 and 20, and offers less resistance to the lateral displacement of the outer end portion of the blade than is the case when the jaw 16 is extended, as shown by Figures 1 and 3.

I claim:

1. A pile wire including a body portion, 10 a blade, and a blade holder fixed to the body portion, said holder comprising opposed jaws yieldingly grasping the sides of the blade, and permitting lateral displacement of the outer end portion thereof, and a plurality of abutments collectively preventing 15 endwise and edgewise movements of the blade interposed between the jaws, said abutments including an outer abutment for the outer end of the blade, and a holding-down abutment for the outer end portion of the blade, both carried by one of the jaws, the arrangement being such that lateral displacement of the outer end portion of the blade disengages it from the outer and holding-down abutments, and permits the removal of the blade from the holder.
2. A pile wire as specified by claim 1, the said outer and holding-down abutments being integral with the jaw by which they 20 are carried.
3. A pile wire as specified by claim 1, the jaws being connected by an integral neck on which the blade-back bears.
4. A pile wire as specified by claim 1, the 25 jaw carrying the outer and holding-down abutments being provided with an opening, formed and arranged to receive a prying tool, whereby the outer end portion of the blade may be laterally displaced.
5. A pile wire as specified by claim 1, the 30 jaws being connected by an integral neck on which the rear end of the blade-back bears, the jaw carrying the outer and holding-down abutments being provided also with an abutment bearing on the forward end of the blade-back.
6. A pile wire including a body portion, 35 a blade, and a blade holder fixed to the body portion, said holder comprising opposed jaws yieldingly grasping the sides of the blade, a blade-back abutment, an inner abutment for the inner end of the blade, an outer

abutment for the outer end of the blade, and a holding-down abutment bearing on an outer end portion of the blade, said abutments collectively preventing endwise and edgewise movements of the blade interposed between the jaws, said outer and holding-down abutments being on one of the jaws, and the outer end of the blade being yieldingly held in engagement therewith by the other jaw, so that the outer end portion of the blade may be laterally displaced, to disengage it from the outer and holding-down abutments, and permit the removal of the blade from the holder.

7. A pile wire as specified by claim 6, the said inner abutment being formed to hold down the inner end of the blade.

8. A pile wire including a body portion, 70 a blade, and a blade-holder fixed to the body portion, said holder comprising opposed jaws yieldingly grasping the sides of the blade, one of the jaws having a head laterally supporting one side of the outer end portion of the blade, the other side of said end portion being laterally unsupported, a blade-back abutment, an inner abutment for the inner end of the blade, an outer abutment for the outer end of the blade, and a holding-down abutment bearing on an outer end portion of the blade, said abutments collectively preventing endwise and edgewise movements of the blade interposed between the jaws, the outer and holding-down abutments being on the head portion and spaced outward from the outer end of the other jaw.

9. A pile wire including a body portion, 75 a blade, and a blade holder fixed to the body portion and comprising opposed jaws yieldingly grasping the sides of the blade and permitting lateral displacement of the outer end portion thereof, and a confining abutment carried by one of the jaws and normally bearing on the margin of the blade at the outer end portion thereof, the arrangement being such that lateral displacement of the outer end portion of the blade disengages its margin from the abutment.

In testimony whereof I have affixed my signature.

JAMES BAGLEY.
